[57] CLAIM

The ornamental design for an infant's drinking mug, as shown and described.

DESCRIPTION

FIG. 1 is a perspective view of a infant's drinking mug showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is an exploded perspective view thereof;

FIG. 9 is a sectional view along line 9—9 in FIG. 6;

FIG. 10 is a sectional view along line 10—10 in FIG. 6;

FIG. 11 is a perspective view of a infant's drinking mug showing a second embodiment of my new design;

FIG. 12 is a front elevational view thereof;

FIG. 13 is a right side elevational view thereof;

FIG. 14 is a left side elevational view thereof;

FIG. 15 is a rear elevational view thereof;

FIG. 16 is a top plan view thereof;

FIG. 17 is a bottom plan view thereof;

FIG. 18 is an exploded perspective view thereof;

FIG. 19 is a sectional view along line 19—19 in FIG. 16; and,

FIG. 20 is a sectional view along line 20—20 in FIG. 16.
